UNITED STATES PATENT OFFICE

MAURICE AUDIBERT, OF VILLEURBANNE, FRANCE

MICROMETRIC SCREW-CUTTING MACHINE

Application filed November 29, 1927, Serial No. 236,454, and in France November 29, 1926.

The present invention relates to screw cutting machines.

One of the objects of the invention is to provide means for controlling, with micrometric precision, the movement of the elements co-operating to cut a thread.

Other objects will appear in the course of the detailed description now to be given with reference to the accompanying drawing in which the single figure illustrates, diagrammatically, one constructive embodiment of the invention.

In some processes of color photography, the photographic emulsion is spread on an engraved cylinder and it is of the utmost importance that the spiral tracing on the cylinder be perfectly regular. The ordinary devices for producing these tracings are of the well-known type in which the means for rotating the cylinder coacts with the tool advancing mechanism. Any irregularity, play or defect in the former is reflected by a corresponding irregularity in the functioning of the latter. It appeared therefore, advisable, first, to make the work rotating mechanism independent of the tool advancing mechanism and, second, to find means for obtaining a strictly regular movement of each of said mechanisms. To insure a constant speed of rotation of the work it is only necessary to employ a synchronous motor fitted with appropriate rheostats and the like for adjusting the speed at any value desired. The control of the movement of the tool carriage is best effected by making use of a gravitationally actuated device whose action is regulated by the flow of liquid through a micrometrically calibrated orifice.

Referring to the drawing, there is shown a cylinder C, intended to be grooved, mounted between points and arranged to be rotated at any constant speed desired by synchronous motor M. Tool O is connected to a heavy piston P which descends by its own weight and displaces liquid L through a micrometrically calibrated valve R.

As will be evident from the foregoing description, rotation of the work is independent of the translational movement of the tool; the former is maintained constant by the syn-

chronous motor, the latter by the action of gravity.

Having now particularly described and ascertained the nature of my said invention, and in what manner the same is to be performed I declare that what I claim is:

In a machine of the class described, means for rotating a piece of work at substantially constant speed, a tool support, a vertical cylinder, a piston slidably mounted in said cylinder and connected to said tool, and a valve associated with said cylinder and adapted to regulate the rate of discharge of liquid therefrom during the descent of the piston under the action of gravity.

In testimony whereof I affix my signature.

MAURICE AUDIBERT.
